HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,288,837.

Specification of Letters Patent. Patented Dec. 24, 1918.

Application filed January 16, 1915. Serial No. 2,553.

To all whom it may concern:

Be it known that I, HENRY P. CLAUSEN, a citizen of the United States, residing at Mount Vernon, in the county of Westchester 5 and State of New York, have invented certain new and useful Improvements in Telephone-Exchange Systems, of which the following is a full, clear, concise, and exact description.

10 This invention relates to telephone exchange systems, and more particularly to such systems of the central energy type, the object of this invention being to provide improved signaling means for such systems.

15 In accordance with one feature of this invention, means are provided at the central office whereby when conversation between two connected subscribers is concluded and the receivers have been restored to the 20 switchhooks, the calling subscriber may, by removing the receiver from the switchhook, cause the operation of recall signaling means at the central office, notifying the operator that the calling subscriber desires another 25 connection, and means are also provided at the central office whereby when conversation between two connected subscribers is concluded and the receivers have been restored to the switchhooks, the called subscriber 30 may, by removing the receiver from the switchhook, disconnect his line from the link circuit apparatus and cause the operation of the usual line signal associated therewith.

35 This invention is illustrated in the accompanying drawing in which all apparatus is shown in its normal and unactuated condition.

There is shown in the drawing a telephone 40 exchange system containing one embodiment of this invention and comprising the usual subscribers' stations A and B and a cord circuit C located at a central office for interconnecting the subscribers' stations. It is 45 believed that this invention will be fully understood from a description of the operation of the system shown in the drawing, and it will be so described.

Supposing subscriber A wishes to converse 50 with subscriber B, A removes his receiver from the switchhook, thereby completing a circuit from battery 5, through one winding of line relay 7, contact 8 of cutoff relay 9, line wires 10 and 11, contact 12 of cutoff

relay 9 and the other winding of line relay 55 7 to battery 5. Current in this path actuates line relay 7 completing a circuit for line signal 13. The operator observing the line signal 13, inserts her answering plug in the jack indicated by signal 13, and thereby 60 completes a circuit from the pole of battery 14, through contact 15 of relay 16, supervisory signal 17, resistance 18, sleeve contacts 19 and 20 of the answering plug and jack and the winding of cutoff relay 9 to 65 ground. Current in this path actuates the cutoff relay 9 which severs the circuit of the line relay 7, effacing the line signal 13. The insertion of the answering plug also completes a circuit from battery 25, through one 70 winding of relay 26, conductor 27, ring contacts 28 and 29 of the answering plug and jack, line wires 10 and 11, tip contacts 30 and 31 of the jack and answering plug, conductor 32 and the other winding of relay 26 75 to battery 25. Current in this path actuates relay 26, opening contact 33 thereof which removes the shunt circuit from resistance 18 and preventing the operation of supervisory signal 17. Actuation of relay 80 26 also closes contact 34, completing a circuit from the live pole of battery 35, through contact 34 of relay 26, contact 36 of relay 37, winding of relay 38, sleeve contacts 19 and 20 of the answering plug and jack and 85 winding of cutoff relay 9 to ground. Current in this path actuates relay 38, connecting operator's telephone set 39 across tip and ring strands 40 and 41 of the cord circuit and opens contact 42. The operator now 90 asks the desired number of the calling subscriber. Finding the desired number to be that of subscriber B, the operator touches the tip of the calling plug to the sleeve of a jack corresponding to B's line to determine the idle or busy condition thereof. If the line tests idle, the calling plug is inserted in the jack, completing a circuit from the live pole of battery 50, through winding of relay 37, contact 52 of relay 95 53, sleeve contacts 54 and 55 of calling plug and jack and winding of cutoff relay 56, to ground. Current in this path actuates cutoff relay 56 cutting line relay 57 from line wires 58 and 59 and actuates relay 100 37, which opens contact 36, thereby releasing relay 38 and disconnecting the operator's telephone set 39 from the cord circuit, and

closing contacts 60 and 61. Insertion of the calling plug also completes a circuit from the live pole of battery 65, through supervisory signal 64, contact 66 of relay 67, contact 52 of relay 53, sleeve contacts 54 and 55 of calling plug and jack, and winding of cutoff relay 56 to ground, operating supervisory signal 64. To signal subscriber B, the operator now depresses a button of locking ringing key 68 to which is connected a source of ringing current of the frequency to which ringer 69 at station B is tuned, and in so doing closes a non-locking way-down contact 70, completing a circuit from the live pole of battery 35, through contact 34 of relay 26, contact 60 of relay 37, winding of relay 71, and contact 70 to ground. Current in this path actuates relay 71, completing a locking circuit therefor through contact 72 thereof, contact 73 of marginal relay 74 to ground, and opening contacts 75 and 76 and closing contacts 77 and 78. Opening of contacts 75 and 76 opens tip and ring cord conductors 40 and 41 and closure of contacts 77 and 78 connects ringing current to one side of the line and ground to the other side. The path for ringing current may be traced from ringing key 68, through relay 74, contact 78 of relay 71, contact 80 of relay 53, ring contacts 81 and 82 of calling plug and jack, line wire 58, condenser 82, ringer 69, line wire 59, tip contacts 83 and 84 of the jack and calling plug, contact 85 of relay 53 and contact 77 of relay 71, to ground. Relay 74 is marginal and will not operate when in series with ringer 69 and condenser 82, but will operate when the relay and condenser are shunted by low resistance. The called subscriber upon removing his receiver from the switchhook, closes a path of low resistance for the ringing current, thereby permitting a greater flow of current through the relay 74. Relay 74 is thereby actuated, opening the circuit of relay 71 at contact 73 of relay 74. Relay 71 thereupon releases, removing ringing current from the line and closes the tip and ring conductors of the cord circuit, completing the talking circuit. The release of relay 71 closes a circuit from battery 86, through one winding of relay 67, conductor 41, contact 76 of relay 71, contact 80 of relay 53, ringing contacts 81 and 82 of calling plug and jack, line wires 58 and 59, tip contacts 83 and 84 of jack and calling plug, contact 85 of relay 53, contact 75 of relay 71, conductor 40 and other winding of relay 67 to battery 86. Current in this path actuates relay 67, opening contact 66, removing the short circuit from about resistance 87 which effaces supervisory signal 64, and closing contacts 88 and 89.

Upon finishing the conversation, subscribers A and B restore their respective receivers to the switchhooks, whereupon relays 26

and 67 release, permitting supervisory signals 17 and 64 to operate to give disconnect signals. If the operator is not busy, the answering and calling plugs are removed from the jacks and all apparatus returns to normal. Suppose, however, that, as is frequently the case during busy periods, the operator does not immediately take down the connection, and suppose further that subscriber A desires to immediately make another call, he removes his receiver from the switchhook, thereby causing supervisory signal 17 to intermittently flash, signifying to the operator that subscriber A desires another connection. The manner in which supervisory signal 17 is caused to flash will now be described. When the receivers were restored to the switchhooks upon the completion of the conversation, a circuit was completed from the live pole of battery 100, through contact 61 of relay 37, winding of relay 101, winding of relay 102, contact 42 of relay 38, contact 33 of relay 26, sleeve contacts 19 and 20 of answering plug and jack, and winding of cutoff relay 9 to ground. Current in this path actuates relays 101 and 102. Actuation of relay 101 opens contact 103 and closes contacts 104 and 105, and actuation of relay 102 opens contact 106 and closes contact 107. Removal of the receiver from the switchhook by subscriber A to make a recall (another call) causes relay 26 to be actuated over the circuit hereinbefore traced. Actuation of relay 26 opens contact 33 and closes contact 108 completing a circuit from the live pole of battery 109, through contact 104 of relay 101, winding of relay 16, contact 108 of relay 26, contact 107 of relay 102, sleeve contacts 19 and 20 of answering plug and jack and winding of cutoff relay 9 to ground. Current in this path actuates relay 16, closing contact 110 and opening contact 15 thereof. Closing of contact 110 completes a circuit from the live pole of battery 111, through interrupter 112, contact 110 of relay 16, supervisory signal 17, contact 107 of relay 102, sleeve contacts 19 and 20 of answering plug and jack, and winding of cutoff relay 9 to ground, causing supervisory signal 17 to flash intermittently to furnish a "recall" signal. The operator observing that supervisory signal 17 is flashing and that supervisory signal 64 is glowing steadily, removes the calling plug from the jack corresponding to the line of subscriber B, which causes relays 37, 101, 102, and 16 to release, and effaces supervisory signals 17 and 64. The release of relay 37 closes the circuit for relay 38 which is thereupon actuated, connecting the operator's telephone set across the conductors 40 and 41 in the manner hereinbefore explained. The operator now communicates with subscriber A and completes the desired 130

connection in the manner already explained. It will be observed that should the receiver of subscriber B be kept off the switchhook and the receiver of subscriber A be restored 5 to and then removed from the switchhook, there will be no flashing of supervisory signal 17, for the circuit of relay 16 cannot be completed due to the short circuit at contact 89 of relay 67 about relay 101 which 10 controls the battery supply to the winding of relay 16. However, should this condition arise, and should the receiver of subscriber B then be restored to the switchhook, relay 101 will be operated, completing the circuit 15 of relay 16 which will thereupon be operated connecting battery and the interrupter 112 in circuit with supervisory signal 17.

Suppose that in the usual telephone exchange systems, after the receivers have been 20 restored to the switchhooks and before the operator has withdrawn the plugs from the jacks, subscriber B (the called subscriber) desires to make a call, the only way to do so would be to cause the flashing of the calling 25 supervisory signal by moving the receiver up and down. This is very unsatisfactory, for the movement of the receiver may be too fast to permit the proper operation of the supervisory relay, hence the supervisory 30 signal does not flash. By the use of a telephone exchange system embodying the present invention, with the foregoing conditions, subscriber B may make a call by simply replacing and then removing the receiver 35 from the switchhook in the usual manner, causing B's line to be disconnected from the connecting circuit apparatus and the operation of the associated line signal. The manner in which this is accomplished will 40 now be described. As before described, when the receivers are restored to the switchhooks, relays 26 and 67 are released and relays 101 and 102 are operated. Now subscriber B removes the receiver from the 45 switchhook, completing the hereinbefore traced circuit through relay 67, causing the operation of this relay. The actuation of relay 67 completes a circuit from the live pole of battery 50, through winding of relay 37, resistance 87, contact 88 of relay 67, contact 105 of relay 101 and winding 115 of relay 53 to ground. Current in this path actuates relay 53 which opens contacts 52, 50 and 85 and closes contact 116 and 117 55 thereof, the closure of contact 116 completing a locking circuit for relay 53 from the live pole of battery 50, through winding of relay 37, contact 116 and winding 118 of relay 53, sleeve contacts 19 and 20 of answering plug and jack and winding of cutoff relay 9 to ground. The opening of contacts 52, 80 and 85 opens tip, ring and sleeve conductors of the cord circuit, disconnecting all apparatus thereof from the line of subscriber B, and causing cutoff relay 56 to re-

lease which thereupon closes contacts 119 and 120 thereof. Line relay 57 is thereupon actuated completing the circuit of line signal 121. The closing of contact 117 of relay 53 completes a circuit from the live 70 pole of battery 125, through contact 117 of relay 33, contact 75 of relay 71, conductor 40 and one winding of relay 67 to ground, maintaining relay 67 actuated to keep supervisory signal 64 operated to furnish a 75 disconnect signal, the circuit therefor being from the live pole of battery 65, through supervisory signal 64, contact 88 of relay 67, contact 105 of relay 101 and winding 115 of relay 53, to ground. Since the line signal 80 121 is operated, this call from subscriber B is handled in the usual manner. It is to be observed, however, that the operation of relay 53 is dependent upon the calling subscriber having replaced the receiver on the 85 switchhook. If the receiver of the calling subscriber has not been restored to the switchhook before the called subscriber removes the receiver to make a call, relays 101 and 102 cannot operate, for both are short-circuited by the path from battery 14, through contact 15 of relay 16, contact 106 of relay 102 and contact 108 of relay 26, so that when the called subscriber B removes the receiver from the switchhook to 90 make a call, the circuit including winding 115 of relay 53 will be open at contact 105 of relay 101, thereby preventing the operation of relay 53.

In accordance with the present invention, 100 the calling subscriber may make another call after the called subscriber has made a call and while the plugs of the cord circuit are still in the jacks of these two subscribers. Under this condition and while the receiver 105 of the calling subscriber is still on the switchhook, relays 37, 53, 67, 101 and 102 are in their actuated positions. Now the calling subscriber removes the receiver from the switchhook, actuating relay 26, which 110 completes the circuit of relay 16 which in turn connects battery 111 and interrupter 112 in circuit with supervisory signal 17. This device thereupon flashes, manifesting 115 a recall signal. The operator observing the flashing of signal 17 removes the calling plug from the jack of the line of the called subscriber, but the signals 17 and 64 will not be released because relays 37 and 53 are locked up through the sleeve contacts of the 120 answering plug and jack. The operator then removes the answering plug from the jack and releases all apparatus associated with the cord circuit, and then re-inserts the answering plug, whereupon the relay 38 is 125 actuated, connecting the operator's telephone set 39 with the cord circuit. The operator now communicates with the calling subscriber and completes the connection in the manner already described. 130

Tip conductors 32 and 40 and ring conductors 27 and 41 of the cord circuit which form the talking strands thereof are joined through condensers 130 and 131 respectively which prevent the flow of signaling currents from one end of the cord circuit to the other. While only one calling and one called subscriber's line is shown for the sake of simplicity, it is to be understood that many such lines will terminate at the central office and that each line will be multiplied through the various sections of the switchboard. While in this description many batteries have been referred to, it is to be understood that 15 a common battery may be substituted therefor, and such is the usual practice.

What is claimed is:

1. In a telephone exchange system, calling and called subscribers' lines, a link circuit, 20 switching means for connecting said link circuit with said lines, recall signaling means permanently associated with one end of said link circuit, means associated with the opposite end of said link circuit for disconnecting said link circuit from the line without disturbing the switching means, and means under the joint control of the calling and called subscribers for controlling the operation of said recall signaling means and said 30 disconnecting means.

2. In a telephone exchange system, calling and called subscribers' lines, a link circuit, switching means for connecting said link circuit with said lines, flashing recall signaling means associated with the answering end of the link circuit, means associated with the calling end of said link circuit for disconnecting said link circuit from the called line without disconnection of the switching 40 means, means controlled by the restoration to the switchhooks of both receivers and a subsequent removal of the calling subscriber's receiver for operating said recall signaling means, and means controlled by the restoration to the switchhooks of both subscribers' receivers and a subsequent removal of the called subscriber's receiver for operating said disconnecting means.

3. In a telephone exchange system, calling 50 and called subscribers' lines, a link circuit, switching means for connecting said link circuit with said lines, an operator's telephone set, switching means operating automatically when the link circuit is connected 55 with the calling line to connect the operator's set with the talking strands of said link circuit and when said link circuit is connected with the called line to disconnect said operator's set therefrom, a recall signal associated with the answering end of said link circuit, means operated upon the restoration to the switchhooks of both subscribers' receivers and a subsequent removal of the calling subscriber's receiver to operate said 65 call signal while said link circuit is still con-

nected with the calling line, and means controlled only by the disconnection of the link circuit from the called subscriber's line for permitting a second operation of the switching means for connecting the operator's telephone set with the talking strands of said link circuit. 70

4. In a telephone exchange system, calling and called subscribers' lines, a link circuit, 75 switching means for connecting said link circuit with said lines, a supervisory signal associated with each end of said link circuit, interrupter means associated with the answering end of said link circuit and operated upon the restoration to the switchhooks of 80 both subscribers' receivers and a subsequent removal of the calling subscriber's receiver to intermittently close the circuit of the supervisory signal associated with the answering end of said link circuit, means associated 85 with the calling end of said link circuit and operated upon the restoration to the switchhooks of both subscribers' receivers and a subsequent removal of the called subscriber's receiver to disconnect the link circuit from 90 the called subscriber's line without disconnection of the switching means, and means for maintaining the supervisory signal associated with the calling end of the link circuit operated after the operation of said disconnecting means. 95

5. In a telephone exchange system, calling and called subscribers' lines, a link circuit for interconnecting said lines, a relay associated with said link circuit and adapted to 100 be controlled from one of the connected substations, a signaling device associated with said link circuit and controlled by said relay, interrupter mechanism, and a second relay controlled from both connected substations 105 and operated through contacts on the first mentioned relay for connecting said interrupter mechanism in circuit with said signaling device.

6. In a telephone exchange system, calling and called subscribers' lines, a link circuit for interconnecting said lines, a supervisory signal associated with said link circuit, a relay associated with said link circuit and adapted to be controlled from one of the 110 connected substations, a second relay energized upon the deenergization of said first mentioned relay and locked up over a circuit completed by the energization thereof, an energizing circuit for said supervisory signal independent of said first mentioned relay, completed upon the energization of said second relay, interrupter mechanism, and a third relay, energized by the restoration to the switchhook of the receiver at the other 115 connected substation when said first mentioned relay is energized, for including said interrupter mechanism in said energizing circuit. 120

7. In a telephone exchange system, calling 125

- and called subscribers' lines, a link circuit connecting said lines, a relay associated with the link circuit and adapted to be controlled from the connected calling substation, an answering supervisory signaling device individual to the link circuit and controlled by said relay, interrupted mechanism, and a second relay jointly controlled from both connected substations and operated through contacts on the first mentioned relay for connecting said interrupter mechanism in circuit with said signaling device.
8. In a telephone exchange system, calling and called subscribers' lines, a link circuit for connecting the lines, a signaling device individual to and in the link circuit, interrupter mechanism serving when in circuit with the signaling device to cause intermittent operation thereof, and means jointly controlled by the operator in connecting the link circuit with the called line and the restoration to and the subsequent removal from its hook of the receiver at the calling station for including the interrupter mechanism in circuit with the signaling device.
9. In a telephone exchange system, calling and called subscribers' lines, a link circuit connected with the calling line, a signaling device associated with the link circuit, interrupter mechanism, a relay conditioned for operation when the link circuit is connected with a called line and operated upon the restoration of the receiver to the switchhook by the calling subscriber, and a second relay operated upon the subsequent removal of the receiver from the switchhook by the calling subscriber for including the interrupter mechanism in circuit with the signaling device.
10. In a telephone exchange system, subscribers' lines, a link circuit having one end connected to a subscriber's line, a supervisory relay associated with the link circuit and controlled from a connected substation, a signaling device, interrupter mechanism, a primary relay conditioned for operation upon the connection of the other end of the link circuit with another subscriber's line and operated upon the deenergization of the supervisory relay, and a secondary relay operated upon the subsequent energization of the supervisory relay to include the interrupter mechanism in circuit with the signaling device.
11. In a telephone exchange system, calling and called subscribers' lines, a link circuit connecting said lines, a supervisory relay, a signaling device, interrupter mechanism, and a relay conditioned for operation upon the deenergization of the supervisory relay and operated upon the subsequent energization thereof to connect the interrupter mechanism in circuit with the signaling device.
12. In a telephone exchange system, calling and called subscribers' lines, a link circuit connecting said lines, a circuit, a signaling device and interrupter mechanism adapted to be serially included in said circuit, and means controlled by the restoration to and the subsequent removal from its hook of the receiver at the calling station for completing the circuit through the interrupter mechanism and the signaling device.
13. In a telephone exchange system, calling and called subscribers' lines, a link circuit for interconnecting said lines, a signaling device and interrupter means associated with the answering end of said link circuit, and a normally short-circuited relay for connecting said signaling device and said interrupter means in circuit, the restoration to the switchhook of the calling subscriber's receiver causing the removal of the short circuit of said relay and a subsequent removal thereof causing the operation of said relay whereby said signaling device furnishes a recall signal.
14. In a telephone system comprising a telephone line, a subscriber's substation connected to said line provided with a substation switch, a manual link circuit provided with a terminal for connecting said telephone line with said link circuit, a signal for said link circuit placed under substation control responsive to such connection, means responsive to an actuation of said substation switch to cause an operating circuit to be closed through said signal, means responsive to the disconnection of the link circuit from the said line circuit to interrupt said signal circuit, and means responsive to a single actuation of said substation switch prior to such disconnection to cause an intermittent operation of said supervisory signal.
15. In a telephone exchange system, a telephone line, a link circuit connected therewith, a supervisory relay for the link circuit, a signaling device, an operating circuit therefor established upon the deenergization of the supervisory relay, interrupter mechanism, and a relay conditioned for operation upon the deenergization of the supervisory relay and actuated upon the subsequent energization thereof to connect the interrupter mechanism in circuit with the signaling device to cause the intermittent operation thereof.
16. In a telephone exchange system, a telephone line, a link circuit connected therewith, a supervisory relay for the link circuit, a signaling device, an operating circuit therefor established upon the deenergization of the supervisory relay, interrupter mechanism, a relay conditioned for operation upon the deenergization of the supervisory relay and operated upon the subsequent energization thereof, and a second operating circuit for the signaling device es-

tablished upon the operation of the second mentioned relay and including the interrupter mechanism.

17. In a telephone exchange system, a telephone line, a link circuit connected therewith, a supervisory relay for the link circuit, a signaling device, an operating circuit therefor established by the deenergization of the supervisory relay, a second operating circuit for the signaling device, interrupter mechanism in the second operating circuit, and a relay conditioned for operation upon the deenergization of the supervisory relay and operated upon the subsequent energization thereof to open the first and close the second operating circuit.
18. In a telephone exchange system, a telephone line, a link circuit connected there-

with, a supervisory relay for the link circuit, a signaling device, an operating circuit 20 therefor established upon the deenergization of the supervisory relay, a normally ineffective intermittent operating circuit for the signaling device, a second relay energized upon the deenergization of the supervisory relay, and a third relay operating 25 while the supervisory and second relays are energized to render the first operating circuit ineffective and the second effective.

In witness whereof, I hereunto subscribe 30 my name this 15th day of January A. D. 1915.

HENRY P. CLAUSEN.
